PIVOTED JAW TYPE, TOGGLE ACTUATED
WRENCH

Benjamin G. Barnett, Dallas, Tex.

Application June 4, 1949, Serial No. 97,129

2 Claims. (Cl. 81—84)

1

This invention relates to utility tools especially designed for household use and it has particular reference to a multi-purpose tool in which the chief characteristic is that of a wrench.

The principal object of the invention is to provide a tool consisting of an elongated and hollow handle having formed thereon an arcuated head or curved and serrated major jaw with which cooperates a curved and serrated minor jaw, the latter being disposed for slideable and pivotal displacement with respect to the major jaw through the medium of a pair of links restricting the pivotal point of the minor jaw to longitudinal movement within the handle and a lever pivoted at one end intermediate the ends of the minor jaw and adapted to pivotally and slideably actuate the latter by virtue of a pivotal connection to said links. Adjustment of the minor jaw in relation to the major jaw is accomplished through the medium of a detent manipulable through the lever into and out of engagement with selected recesses in longitudinally spaced relationship in the rear face of the handle.

Another object of the invention is to provide a tool as set forth which besides serving as a wrench for removing screw covers from jars and the like, is equipped with a screw driver bit and can opener pivotally mounted in the free end of the handle; a cork screw pivoted in the end of the minor jaw operating lever; a hammer head removably carried by the end of the major jaw; a nail puller and wrecking claw formed on the end of the major jaw and wire cutting means formed jointly on the major and minor jaws.

Other objects will appear as the description proceeds, taken in connection with the accompanying drawings wherein:

Figure 1 is a side elevational view of a utility tool constructed according to the present invention.

Figure 2 is a sectional view taken on line 2—2 of Figure 1.

Figure 3 is a fragmentary plan view of the major jaw and showing the hammer attachment in detached relationship therewith.

Figure 4 is a sectional view of the hammer attachment taken on line 4—4 of Figure 3.

Figure 5 is a transverse sectional view of the handle taken on line 5—5 of Figure 1.

Figure 6 is a transverse sectional view of the minor jaw actuating lever, taken on line 6—6 of Figure 1, and

Figure 7 is a transverse sectional view taken on line 7—7 of Figure 1.

Continuing with a more detailed description of

the drawing, reference numeral 10 denotes the handle of the tool, which latter is die-formed preferably from sheet metal. The handle is substantially oval in transverse section, the inner face being open the major part of its length to define a slot 11 for the purpose to be presently described. In the rear face of the handle and opposite the slot 11 is formed a series of recesses defining teeth 12.

10 The upper end of the handle 10 is curved into a major jaw 13 whose arcuated work engaging face 14 is serrated, as shown. The end of the jaw is forked at 15 to serve as a wrecking claw and nail puller and is shaped to define a socket 16 to receive the shank 17 of a hammer head 18. The hammer head 18 is slotted at 19 (Fig. 4) in order to receive the tip of a minor jaw member 20 when the latter is closed into the position shown in dotted lines in Figure 1.

15 The minor jaw 20 is also arcuated and its work engaging portion 21a is likewise serrated. The inner end of the minor jaw enters the slot 11 in the handle 10 and has pivoted thereto at a on each side a link 21. The links 21 are constrained 20 to slide longitudinally within the handle 10 and between their lower ends is pivoted at b, an end of a link 22. The link 22 extends outwardly 25 through the slot 11 in the handle and is pivoted at its opposite end at c to a lever 23.

30 The lever 23 is bifurcated at its upper end to receive the lower edge of the minor jaw 20, to which it is pivoted at d.

It is apparent from the foregoing that the links 35 21 may be freely moved longitudinally in the handle by reciprocating the lever 23 to thus adjust the minor jaw with respect to the major jaw and to accommodate the jaws to screw lids of jars or other work of different sizes. When the desired 40 adjustment is obtained, the position of the minor jaw is secured by a protuberance 24, formed on the inner end of the short link 22 which joins the lever 23 with the parallel links 21. The protuberance 24 is engaged selectively with the recesses 12, thus providing a fulcrum for the link 22 as the lever 23 is manipulated toward and away from the handle to swing the minor jaw in relationship to the major jaw on the pivot a. The clearance between the links 21 and the walls of the handle 10 is such that the protuberance 24 may be displaced in relation to the teeth 12.

45 The major jaw has a half-round recess 25 formed on its inner surface adjacent the work engaging portion 14 thereof. This recess cooperates with a like recess 26 opposite the same in the work engaging face 21a of the minor jaw 20 to serve as a wire cutter when the minor jaw is

moved to operate in the extreme raised position in relation to the major jaw.

Pivoted at 21 in the end of the handle 10 is a can opening blade 28 and a screw driver bit 29. A cork screw 30 is pivoted at 31 in the lever 23. The elements 28 and 29 are foldable into the hollow of the handle while the cork screw is concealed in like manner in the lever 23. In the outer end of the minor jaw 20 is a hook 32 which is adapted to remove crown caps from bottles.

Manifestly, the construction as shown and described is capable of some modification and such modification as may be construed to fall within the scope and meaning of the appended claims is also considered to be within the spirit and intent of the invention.

What is claimed is:

1. A wrench type tool comprising a hollow handle having a longitudinal slot therein and an arched head defining a major jaw having a serrated work engaging portion, a minor jaw having a serrated work engaging surface curved opposite to that of said major jaw, parallel links slidable longitudinally in said handle and to which said minor jaw is pivoted at one end for oscillating displacement in relation to said major jaw, a plurality of aligned teeth interiorly of said handle opposite the slot therein, a lever pivoted at one end to said minor jaw intermediate its ends, means pivotally connecting said lever intermediate its ends to the ends of said links opposite the pivot of said minor jaw whereby oscillation of said lever will impart motion to said minor jaw and means adjacent the pivotal point between said lever and links and engageable selectively with the teeth in said handle to hold said minor jaw in adjusted positions in relation to said major jaw.

2. A wrench type tool comprising a hollow, longitudinally slotted handle having a longitudinal row of internal teeth opposite and parallel with the slot in said handle, parallel links movable longitudinally in said handle and capable of limited lateral displacement between said slot and said row of teeth, a head formed on said handle defining a major work engaging jaw, a minor work engaging jaw having one end disposed in the slot of said handle and pivoted to the upper ends of said parallel links, a lever pivoted at one end intermediate the ends of said minor jaw and movable towards and away from said handle, a link pivoted to said lever intermediate its ends and whose opposite end extends into said handle through the slot therein below said minor jaw and pivoted to the lower ends of said parallel links, and means carried by said link engageable selectively with the teeth in said handle for holding said minor jaw in adjusted positions with respect to said major jaw.
